UNITED STATES PATENT OFFICE.

ALBERT FISCHER, OF DETROIT, MICHIGAN.

CAR-COUPING.

SPECIFICATION forming part of Letters Patent No. 275,814, dated April 17, 1883.

Application filed July 17, 1882. (No model.)

To all whom it may concern:

Be it known that I, ALBERT FISCHER, a citizen of the United States, residing at Detroit, in the county of Wayne and State of Michigan, have invented a new and useful Improvement in Car-Couplings, of which the following is a specification.

My invention relates to that class of couplings which are self-acting and intended to prevent the great loss of life which to the present time almost daily results from the usual modes of coupling, especially freight-cars. I attain this object by the device illustrated in the following drawings, in which—

15 Figure 1 is a perspective view of device with the pin uncoupled. Fig. 2 shows the coupling-pin plate detached and without the pin. Fig. 3 is a longitudinal sectional view of device through a vertical cut down the center of the draw-head. Fig. 4 is a perspective view of the under side, showing slot, pin, &c. Fig. 5 shows device attached to a car and as it appears when coupled, together with the uncoupling attachment.

25 Similar letters refer to similar parts throughout the several views.

A is an ordinary-shaped draw-head, cast with two slots—one on its upper and one on its under side. The upper slot, *a*, commences directly back of the bumper, where the coupling-pin is usually inserted in the ordinary draw-head, and extends back of sufficient length to allow the coupling-pin to swing freely through. The under slot, *a'*, Fig. 4, is shorter than the upper one, but of sufficient length to allow the coupling-pin to swing freely when in place. These slots are a trifle wider than the diameter of the coupling-pin. Directly back of the upper slot, at the end of the draw-head, is cast 35 a solid post, *b*, which has a projection on its front side to limit the lifting of the coupling-pin to about the position shown in Fig. 1. The top of this post should not be higher than the bumper. Its purpose is to hinge the coupling-pin plate *B* thereto. This plate is cast of sufficient length to extend from where hinged to post *b* up to the end of slot *a*, or against the bumper, and is slotted or forked to coincide with said slot *a* when the plate is down in place. 45 This plate *B* may be a little narrower than the draw-head, and of sufficient thickness to weigh about twenty pounds. At the center of the

free or forked end of this plate is hung or hinged the coupling-pin *C*, a bolt with a nut being used as the hinge-pin, so that in case the coupling-pin should be broken a new one can be quickly and easily put in its place. Across the slot on top of the coupling-pin plate is cast a bridge or arch, *c*, of sufficient spring to allow the coupling-pin to swing entirely free of the inside cavity of the draw-head, but prevent it from going over on top. To the top of this arch *c* is attached the uncoupling arrangement by the link *d* and eyelet *e*, Fig. 5. The uncoupling is accomplished from the top of the car 60 by means of the vertical rod (flat) *f*, which is kept in position against the end of the car by the U-shaped straps *g* *g*, and whose lower end rests on the draw-head. To this rod the link *d*, or its equivalent, a chain, is attached by eyelet *e'*. At the upper end of this rod is the handle *h*, at such a distance from the top of the car that when pulled up in uncoupling it will not project above the same. In conjunction with this lifting-rod *f* are two side rods or levers, 65 *j* *j*, (also flat,) which are connected with the lifting-rod by the pin *k*, which is rigidly fastened or screwed to the rod *f*, and projects therefrom to its flanged head or a pin sufficiently to allow the forks or slots *l*, at or near the ends of 70 the levers *j* *j*, to enter and act thereon. These levers extend nearly to the sides of the car, and are placed at any desirable height, with proper handles, *m* *m*, and are secured in place by the fulcrum-bolts *n* *n*, or any equivalent device, and the bent or U-shaped straps *o* *o*, fastened to the car between the fulcrum-bolts and the handles of the levers. A wedge-shaped piece or tooth, of iron, *p*, is fastened to the back of the lifting-rod *f*, about midway between the 75 pin *k* and upper strap *g*. This piece is made to hug the counter-plate *r*, which has corrugations to fit the piece *p*, and is fastened to the car in the line on which *p* moves when uncoupling. It is of sufficient length to engage with 80 it during such operation, the spring of the rod *f* between the pin *k* and the upper strap *g* being sufficient, with this ratchet device, to hold the coupling-pin drawn up, as in Fig. 1, and yet allow the levers to easily operate in 85 placing it in position to couple when desired.

The working of the device is obvious. When not held out of place designedly, the coupling-pin is always ready to receive the coupling-

link and secure the connection instantaneous and sure. The uncoupling is sufficiently obvious from the foregoing explanation and drawings.

5 What I claim as my invention, and desire to secure by Letters Patent, is—

1. In a car-coupling, the draw-head formed with slots a a' and the post or stop b , in combination with the plate B , hinged to the said
- 10 post b , and provided with bridge c , tripping devices, and the hinged coupling-pin C , substantially as shown and described.

2. The draw-head A , formed with slots a a' , and provided with stop or post b , in combination with the hinged slotted plate B and coupling-pin C , hinged thereto, and the link D , substantially as shown and described. 15

ALBERT FISCHER.
